UNITED STATES PATENT OFFICE

LYMAN L. LORD, OF BOSTON, MASSACHUSETTS, ASSIGNOR TO E. B. BADGER & SONS COMPANY, OF BOSTON, MASSACHUSETTS, A CORPORATION OF MASSACHUSETTS

APPARATUS FOR CORRUGATING METAL TUBES

Application filed June 20, 1928. Serial No. 286,930.

This invention relates to apparatus for corrugating metal tubes and more particularly to apparatus of the type embodying relatively movable corrugated die or mold sections adapted to be applied to the outside of the tube, after which the tube is subjected at the same time to end pressure longitudinally and to internal fluid pressure, the object of the invention being to facilitate the forming operation and to provide devices quickly and readily applicable to and removable from the tubes and designed to cooperate with the means through which the end pressure and internal pressure are applied to prevent leakage during the several steps performed in the functioning of the apparatus.

In carrying out the operation above referred to, as, for example, in the formation of corrugated expansion joints for steam or hot water lines, a cylindrical metallic tube is placed with its ends in abutting relation to two separated and opposing heads which are capable of being forced relatively toward each other to provide the end pressure referred to. Means are also provided to admit hydraulic or other fluid pressure to the interior of the tube so that, as the tube is contracted under the end pressure, the internal pressure causes it to expand in exact conformation to the internal formation of the die or mold sections which are initially located at suitable, spaced distances apart but approach each other as the forming operation proceeds.

One object of the present invention is to provide an end closure which can be readily applied to the tube prior to its installation in the apparatus and preferably without the necessity of special preparation of the tube therefor, but which can be readily removed from the tube after its completion while at the same time, under the internal pressure, it serves to cooperate with the abutting heads as a part of the machine itself automatically to engage the walls of the tube and the pipe or conduit through which fluid pressure is admitted thereto or to pack the end of the tube and to prevent leakage therefrom.

The invention will be best understood by reference to the following description when

taken in connection with the accompanying illustration of one specific embodiment thereof, while its scope will be more particularly pointed out in the appended claims.

In the drawings:

Fig. 1 is a sectional elevation showing the apparatus for forming corrugated metal tubes embodying one form of the invention, the tube being shown in its relationship to the machine as initially installed therein;

Fig. 2 is a view showing the relationship of the parts after fluid pressure has been admitted to initially set the tube against the surrounding dies;

Fig. 3 shows the relationship of the parts after the corrugated formation of the tube has been completed;

Fig. 4 is a cross sectional elevation taken through one of the sectional die members;

Fig. 5 is an end elevation of one of the end closures on an enlarged scale; and

Fig. 6 is a sectional elevation taken through the same end closure showing its relationship to the tube when in position therein.

Referring to the drawings and to the embodiment of the invention which is there shown for illustrative purposes, the same comprises the bed plate 11 on which there is provided at one end the upright stationary head 13 and at the opposite end the head 15, the latter serving as a guiding support for the horizontally moving plunger 17 carrying the movable head 19, between which and the stationary head 13 the tube 21 is adapted to be placed with its ends in abutting relation to each.

The plunger 17 and head 19 are capable of being moved toward the stationary head 13 under a pressure sufficient to collapse the largest and heaviest tube to be corrugated, and the power employed for this purpose may be either hydraulic or other fluid pressure or mechanical power transmitted to the plunger 17 through appropriate gearing.

The two stationary heads 13 and 15 are connected by four or more tie rods 23 which are located outside of the space occupied by the mold or die sections, the movable head

19 being slidably related to such tie rods. The stationary heads are also connected by two other rods 25 which pass through the movable head and through the lower half of each mold section and serve as supports therefor as well as guides for the individual mold sections in the movement thereof during the formation of the corrugations.

Each mold or die section (see Fig. 4) is formed in two separable parts comprising a lower half 27 slidably mounted on the guide or supporting rods 25 and an upper mating half 29. The lower half is provided with dowel pins 31 registering with recesses in the upper half 29. After the tube has been positioned in the machine, the upper half of each mold section is clamped to the lower half by means of bolts 33 which are pivoted at 35 in the slotted ends of laterally projecting lugs 37 on the lower half of the mold, the bolts being swung up to enter the open ends of the similarly slotted lugs 39 presented by the upper half 29 and clamped tightly in position by means of the nuts 41. The upper half of each section can be readily removed after the formation of the tube by loosening the nuts 41 and swinging the bolts back and down out of engagement.

The mold sections (Figs. 1 to 3) comprise the end sections 29^a which are each shaped to form one-half of an end corrugation of the tube, leaving the portion of the tube projecting beyond the end corrugation in finished cylindrical shape and of its original diameter. The mold sections also comprise other intermediate sections 29^b shaped each to form a complete intermediate corrugation, so that when the tube is completed and the die sections are brought into contacting relation (as shown in Fig. 3) they provide a sectional mold which is a true matrix of the corrugated tube required to be formed. The shape and dimensions of the corrugations may be varied within wide limits and the number of corrugations may be varied by increasing or decreasing the number of intermediate mold sections, there being herein shown for purposes of exemplification two intermediate die sections 29^b for the formation of a tube with three corrugations.

To apply fluid pressure internally within the tube during the process of formation any suitable means may be employed, but herein there is provided a pump 43, diagrammatically shown in Fig. 1, connected to supply water or other fluid under pressure to the interior of the tube 21 by means of a pipe 45 which passes through the stationary head 13. Means are preferably provided to supply fluid pressure of any desired amount and to regulate the same, there being herein shown for this purpose, and as exemplifying such devices, the manually operated valve 47 for controlling the supply from the pump, the

manually operated relief valve 49 by which the pressure may be manually relieved, and the automatic relief valve 51 of any desired type which may be set to keep the pressure automatically at some desired limited amount. A pressure gauge 53 is also provided by means of which the operative can be advised of the fluid pressure within the tube.

To close the end of the tube against leakage, an end closure is provided (see Figs. 5 and 6) comprising the disk-like plate 55, preferably of rubber or other like compressible material, clamped by means of the clamping bolts 57 between an inner metallic backing disk 59 and an outer circular face plate 61. The rubber plate 55 is of such a size that in its normal condition, when uncompressed, it can be forced into the end of the tube 21, the backing plate and face plate being of lesser diameter than the inside diameter of the tube. The end closure for the end of the tube abutting against the movable head 19 is imperforate, while the closure for the opposite end of the tube is provided with the central perforation 63 of such size as to cause the rubber to grip tightly about the walls of the fluid supply pipe 45 when the tube with its end closure is placed in position in the machine. The outer side of the face plate 61 is provided with a series of ribs 65 providing seating walls which, when brought flush with the end of the tube, cause the rubber to engage the inner walls of the tube at a substantial distance from the end of the tube, so that, for an object hereinafter explained, a substantial outward movement of the end closure relatively to the tube may take place without causing the rubber to disengage from the inner walls of the tube.

In the use of this apparatus an imperforate end closure is installed in one end of a cylindrical tube blank (see Fig. 1), and a centrally perforated end closure, of the type shown in Figs. 5 and 6, is installed in the opposite end of the tube. The end closures are installed by forcibly pressing the rubber disks into the ends of the tubes far enough to bring the edges of the seating ribs 65 approximately flush with the ends of the tubes. After the end closure has been forced into the tube, the bolts 57 may be set up tightly if desired to compress the rubber plate and expand it into closer fitting contact with the inner walls of the tube.

The upper halves 29 of the several die sections having been removed and the movable head 19 retracted, the tube is then placed in the machine resting on the lower halves 27 of the die sections, the perforated end closure being forced over the end of the fluid pressure supply pipe 45. The movable head 19 is then moved up to bring the ends of the tube in abutting relationship to the two heads 13 and 19 and the upper halves of the die sections placed loosely in position on the lower

halves. The die sections are then separated by spaced intervals such as to leave the required amount of metal between their respective points of contact to form the final corresponding corrugations, and the upper die section halves are then clamped securely in place. The tube is then ready to be formed.

The forming operation may be carried out in various ways, but preferably the valve 47 is opened to fill the interior of the tube with fluid, after which, and before applying power to move the head 19 longitudinally, the fluid pressure is brought to a point sufficient to expand the tube into firm seating contact against the surrounding dies.

The internal pressure thus exerted against each end closure forces the face plate 61 into close seating contact with the corresponding head 13 or 19, compressing the rubber disk 20 between the face plate and the backing plate, causing it to further expand and forcibly engage the inner walls of the tube, securing the effect of a tightly packed piston capable of preventing leakage under the highest pressure 25 usable in practice. At the same time the compression of the rubber plate causes the rubber in the end closure abutting against the head 13 to grip tightly about the pipe 45, similarly preventing leakage at that point.

Having brought the fluid pressure up to this point, the operative preferably increases the internal pressure to effect a slight and barely visible initial set in the tube, which is shown in possibly exaggerated form in Fig. 2. 30 This is required to be only such as will definitely position the contacting die sections with relation to the outer walls of the tube, so that in the subsequent contracting operation they approach each other while maintaining the same definite relationship to their 35 initial setting points on the tube.

This initial set tends to shorten the longitudinal dimension of the tube and to withdraw one or both ends from its abutting relationship to the adjoining head. When this 40 takes place, however, the end closure under the internal fluid pressure maintains the same seating relationship to the head and being relatively movable within the tube, the latter 45 contracts longitudinally with relation to the end closure which, however, continues to function as an efficient packing for the tube.

This condition is represented in Fig. 2. When this point is reached, power is applied 50 to move the head 19 to apply longitudinal end pressure, thereby forcing the tube outwardly into and against the contoured die sections to form the corrugations until the condition 55 represented in Fig. 3 is reached, the internal fluid pressure being preferably maintained throughout this operation either by means of the manually actuated relief valve 49 or the automatic relief valve 51 at substantially the 60 pressure which was employed in securing the initial set. As soon as the head 19 is moved

to apply the longitudinal end pressure, the ends of the tubes are again brought into abutting contact with the respective heads and again move relatively to the end closures, the latter continuing to function as before under 70 the influence of the internal pressure to efficiently close and pack the ends of the tubes.

During the longitudinal contraction of the tube and the radial expansion of portions thereof the die sections 27 and 29 approach 75 each other, and, after the heads and the dies have been brought to the relationship represented in Fig. 3, where the die sections have been brought into close contact, the power is cut off from the movable head, the internal 80 fluid pressure relieved and the relief valve 49 opened to drain or partially drain the water from the inside of the formed tube. The head 19 is then retracted, the upper die sections removed, the corrugated tube withdrawn 85 from the machine, and the end closures removed, their removal being facilitated, if required, by loosening the clamping bolts 57.

While I have herein shown and described for purposes of illustration one specific embodiment of the invention, it is to be understood that extensive deviations may be made therefrom without departing from the spirit thereof.

Claims:

1. An apparatus for corrugating metal tubes having relatively movable corrugated mold sections adapted to be applied to the outside of the tube, means for applying end pressure longitudinally to the tube comprising opposing heads between which the tube may be placed with its ends in abutting relation to each with means for forcing said heads relatively toward each other, means for supplying pressure fluid to the interior of the tube to expand the tube from within, and an end closure for the tube adapted when in the tube to abut against one of said heads, said pressure fluid supplying means including a pipe also passing through said end closure, said closure being relatively movable within the tube and self expanding under the internal fluid pressure therein while abutting against said head to forcibly engage the inner walls of the tube and the outer walls of said pipe to prevent leakage.

2. An apparatus for corrugating metal tubes having relatively movable corrugated mold sections adapted to be applied to the outside of the tube, means for applying end pressure longitudinally of the tube comprising opposing heads between which the tube may be placed with its ends in abutting relation to each, means for forcing said heads relatively toward each other, means for supplying pressure fluid to the interior of the tube to expand the tube from within, and an end closure for the tube adapted when in the tube to abut against one of said heads, said closure being relatively movable within

the tube and self expanding under the internal pressure therein while abutting against said head to forcibly engage the inner walls of the tube.

5. An apparatus for corrugating metal tubes having a corrugated mold adapted to be applied to the outside of the tube, means for applying pressure longitudinally to the tube comprising opposing heads between 10 which the tube may be placed in abutting relation to each, means for supplying fluid pressure to the interior of the tube, and an end closure adapted to fit the interior of the tube and to abut against one of said heads, 15 said closure being relatively movable within the tube and self expanding under the internal pressure therein to forcibly engage the inner walls of the tube.

4. A machine for corrugating metal tubes 20 having a corrugated mold adapted to be applied to the outside of the tube, means for applying end pressure longitudinally to the tube, and means for supplying pressure fluid to the interior of the tube, the machine including an end closure for the tube frictionally engaging the inner walls of the tube and self expanding under the internal fluid pressure within the tube to forcibly engage the inner walls of the tube and prevent leakage 25 therefrom.

5. A machine for corrugating metal tubes having means for applying end pressure longitudinally of the tube comprising a stationary head and a movable head, and a pipe 35 passing through the stationary head to the interior of the tube to supply fluid pressure thereto, including an end closure for the tube frictionally engaging the inner walls thereof and compressible under the internal pressure 40 sure to forcibly engage the inner walls of said tube and the outer walls of said pipe to prevent leakage therefrom.

6. A machine for corrugating metal tubes having means for applying end pressure longitudinally of the tube comprising a stationary head and a movable head, and a pipe 45 passing through the stationary head to the interior of the tube to supply fluid pressure thereto, including an end closure for the tube frictionally engaging the inner walls thereof and compressible under the internal pressure 50 to forcibly engage the inner walls of said tube and the outer walls of said pipe to prevent leakage therefrom, the same comprising a face plate having seating walls 55 adapted to engage one of said heads, a disk of yieldable material the periphery of which frictionally engages the inner walls of the tube, and a backing plate between which and 60 the face plate the yieldable disk is secured.

7. A machine for corrugating metal tubes having relatively movable corrugated mold sections adapted to be applied to the outside of the tube, means for applying end pressure 65 longitudinally of the tube comprising oppos-

ing heads between which the tube may be placed in abutting relation to each, means for forcing said heads relatively toward each other, and means for supplying fluid pressure to the interior of the tube, the machine 70 including end closures frictionally engaging the inner walls of the tube and adapted to abut against the respective heads.

8. A machine for corrugating metal tubes having relatively movable corrugated mold 75 sections adapted to be applied to the outside of the tube, means for applying end pressure longitudinally of the tube comprising opposing heads between which the tube may be placed in abutting relation to each, means for forcing said heads relatively toward each other, and means for supplying fluid pressure to the interior of the tube, the machine including cylindrical end closures fitting the 80 opposite ends of the tube to pack the same against leakage, said closures being relatively movable in the tube.

9. A machine for corrugating metal tubes having relatively movable corrugated mold 85 sections adapted to be applied to the outside of the tube, means for applying end pressure longitudinally of the tube comprising opposing heads between which the tube may be placed in abutting relation to each, means for forcing said heads relatively toward each other, and means for supplying fluid pressure to the interior of the tube, the machine including an end closure within the end of the tube adapted to be forced into engagement with the walls of the tube under the 90 internal pressure within the same to pack the same against leakage.

10. A machine for corrugating metal tubes having relatively movable corrugated mold 95 sections adapted to be applied to the outside of the tube, means for applying end pressure longitudinally of the tube comprising opposing heads between which the tube may be placed in abutting relation to each, means for forcing said heads relatively toward each other, and means for supplying fluid pressure to the interior of the tube, the machine including an end closure fitting the interior of the tube and comprising a disk of yieldable material, a backing plate and outer face plate 100 having expanding seating walls adapted to seat against the abutting head.

11. An apparatus for corrugating metal tubes having relatively movable corrugated mold sections adapted to be applied to the outside of the tube, means for applying end pressure longitudinally to the tube comprising opposing heads between which the tube may be placed with its ends in abutting relation to each with means for forcing the heads relatively toward each other, means for supplying fluid pressure to the interior of the tube to expand the tube from within, and an end closure for the tube disconnected from 115 said heads and applicable to the tube prior 120 to the application of the mold sections.

to its installation in the machine, said end closure preventing leakage from the tube during the corrugating operation.

12. An apparatus for corrugating metal tubes having relatively movable corrugated mold sections adapted to be applied to the outside of the tube, means for applying end pressure longitudinally to the tube comprising opposed relatively movable heads between which the tube may be placed with its ends in abutting relation to each with means for forcing said heads relatively toward each other, means for applying pressure fluid to the interior of the tube to expand the tube from within, and pressure tight packing means engaging the walls of an end of the tube to prevent leakage therefrom, said packing means permitting relative movement between the tube and the adjoining head when the tube is shortened by preliminary application of internal pressure.

13. A machine for corrugating metal tubes having relatively movable, corrugated, mold sections adapted to be applied to the outside of the tube, means for applying end pressure longitudinally to the tube comprising opposed, relatively movable heads between which the tube may be placed with its ends in abutting relation to each, means for supplying pressure fluid to the interior of the tube to expand the tube from within and shorten it longitudinally, and means for closing an end of the tube to prevent leakage therefrom when the tube is shortened by preliminary application of internal pressure and an end thereof caused to withdraw from the adjoining head, said means comprising an end closure for the tube frictionally engaging the inner walls thereof to prevent leakage therefrom, said end closure being relatively movable within the tube.

In testimony whereof, I have signed my name to this specification.
